COIN CONTROLLED MECHANISM

Myron H. Richardson, Chicago, and Albert E. Gebert, Wilmette, Ill., assignors to Advance Machine Company, Chicago, Ill., a corporation of Illinois

Application January 14, 1932, Serial No. 586,499

15 Claims. (Cl. 194—92)

This invention relates to improvements in coin controlled mechanism, and one of the objects of the same is to provide an improved mechanism of this character which will receive a coin of a predetermined value or denomination and permit the same to move into an operative position with respect to the coin actuated mechanism, but which will detect counterfeits, undersized coins, slugs, washers, and in fact any token except the standard coin or token for which the mechanism is designed, and prevent them from actuating the mechanism.

To the attainment of these ends and the accomplishment of other new and useful objects as will appear, the invention consists in the features of novelty in substantially the construction, combination and arrangement of the several parts, hereinafter more fully described and claimed and shown in the accompanying drawings illustrating this invention and in which

Figure 1 is a side elevation of mechanism of this character constructed in accordance with the principles of this invention and showing the parts in their normal position.

Figure 2 is a view similar to Figure 1, with parts omitted and with parts broken away.

Figure 3 is a view similar to Figure 1, showing the position the parts will assume when a proper check or token is inserted and the mechanism actuated, and just before the token is ejected from the mechanism.

Figure 4 is a sectional view taken on line 4—4, Figure 3.

Figure 5 is a sectional view taken on line 5—5, Figure 3.

Figure 6 is an irregular sectional view taken on line 6—6, Figure 1.

Figure 7 is an irregular sectional view taken on line 7—7, Figure 1.

Figure 8 is an irregular sectional view taken on line 8—8, Figure 1.

Figure 9 is a view similar to Figure 7, showing the position the parts will assume when an iron disc or washer is inserted in the mechanism.

Figure 10 is a view of a portion of the check carrier and the detecting mechanism, showing the position the parts will assume when an iron washer is inserted.

Figure 10a is a sectional view taken on line 10a—10a, Figure 10.

Figure 11 is a view similar to Figure 10, with the check carrier advanced with respect to Figure 10, and the position which the parts will assume when a small coin or disc is inserted.

Figure 12 is a sectional view taken on line 12—12, Figure 11.

Referring more particularly to the drawings, the numeral 15 designates a suitable face plate and secured to and projecting laterally from the rear of this plate is a supporting plate or member 16, which may be of any desired length and width, and secured to the top of the plate adjacent one face thereof and spaced therefrom is a member 17 which preferably terminates short of the transverse center of the plate.

Another member 18 is secured to the face of the plate 16 adjacent the bottom thereof and is spaced therefrom, and the two members or plates 17 and 18 together with the plate 16 constitute a guide in which a check carrying member 19 reciprocates. The check carrying member is preferably of a length greater than the length of the plate 16. The face plate 15 is provided with a slot 15a which registers with the space between the guides 17 and 18, and projecting forwardly from the face plate is a casing designated generally by the reference numeral 20, the interior of which has communication with the slot in the face plate 15, so as to receive the portion of the check carrying member which projects through the slot in the face plate 15. One wall of the casing 20 is provided with an elongated slot 21, and a handle or operating device 22 extends through the slot and is secured to the check carrying member 19 and serves as a means whereby the check carrying member may be reciprocated. The slot is of a length to permit a full movement of the check carrying member.

The walls of the casing 20 adjacent the face plate 15 are preferably cut away as at 23 and the portion of the check carrier 19 which moves in the casing 20 is shaped to form a check receiving seat 24, which latter is adapted to be moved into register with the cut away portions 23 in the wall of the casing 20 so as to facilitate the insertion of the check or token into the check seat 24 in the check carrier 19.

A coil spring 26 is anchored by one extremity as at 27 to a fixed portion of the mechanism such as the plate or member 17, and the other end of the coil spring is secured as at 28 to the check carrying member 19. The normal tendency of the spring 26 is to move the check carrying member into the position shown in Figure 1, so that a check can be inserted into the check seat and the handle or operating knob 22 engaging one end of the slot 21 serves as a stop for limiting the movement of the check carrier 19 under the stress of the spring 26.

55

Carried by one of the walls of the casing 20 and secured by one end thereto in any desired or suitable manner, such as by means of fastening devices 29, is a resiliently yielding member 5 preferably in the form of a flat or leaf spring 30. The free end of this spring passes through the slot 15^a in the face plate 15 and stands adjacent the face of the plate 16, opposite to the face adjacent which the check carrier 19 slides. 10 The spring 30 is provided with a lateral projection 31 which projects through an opening 32 in the plate 16 and is disposed at any suitable distance from the free end of the spring. Another lateral projection in the form of a lug 33 15 is secured to the spring 30 preferably adjacent the free end thereof, and this projection 33 extends through an opening 34 in the plate 16 and is adapted to enter a slot 35 in the check carrier slide 19, for a purpose to be set forth. The projection 31 is of such a length that it will enter the check seat 24 through the side thereof when the check seat is adjacent thereto, and at the same time the lug or projection 33 will under the influence of the inherent resiliency of the spring 30, be projected into the slot 35 of the 20 check carrier 19. The projection 31 is so located that as the check seat 24 is moved into position to receive the check, a portion of the check carrier 19 will engage the projection 32 by reason of the inclined surface 36 of the check carrier 19 contacting with the end of the projection 31. This will also retract the projection 33 and cause it to move out of the slot 35.

When the projection 33 is in the slot 35, it will 35 be manifest that the check carrying slide 19 cannot be moved forwardly by reason of the lug 33 engaging the end of the slot. This will be the condition when a thin check is inserted in the check seat.

When, however, a check or token of the proper size and denomination is inserted in the check seat and the check carrier 19 moved forwardly, the check will engage the projection 31 to move it out of the check seat and press back the spring 30, causing the lug 33 to be withdrawn from the slot 35 in the check carrier slide 19, thereby permitting the check carrier to be moved forwardly to the full extent of its movement.

Arranged adjacent the path of movement of the check in the check carrier is a magnet 37 which is supported for lateral movement preferably by means of a flat or leaf spring 38 at its end as at 39, the end to which the magnet is attached being free for lateral movement. The magnet 37 is preferably of a horse shoe or U shaped type, and as the side of the check seat 24, which moves adjacent the magnet, is opened, an iron check inserted in the check seat will be attracted by the magnet and moved laterally out of the check seat. The magnet being mounted 55 upon the leaf spring 38 is itself adapted to be bodily moved laterally so as to completely remove the spurious check from the check seat (see Figure 9).

Any suitable means may be provided for thus 65 moving the magnet, but a simple and efficient means embodies a lug or projection 40 (see particularly Figures 3 and 4) which is adapted to engage a portion 41 carried by the spring 38, the extremities of such portion being deflected as 70 at 42-43, so as to facilitate the passing of the projection 40 under the portion 41 of the spring 38, thereby moving the spring 38 to the position shown in Figure 4, and with it the magnet 37, thereby completely removing the attracted token 75 from the check seat.

A finger 44 may be provided which is suitably supported and arranged to pass between the legs of the magnet 37. This finger is preferably stationary and passes between the legs of the magnet when the latter is bodily shifted, so as to engage the token carried by the magnet to detach the same therefrom so that the token will drop or be ejected. 5

Carried also by the portion 41 of the spring 38 is a laterally projecting finger 45 which is adapted to enter the check seat through the side thereof, when the check seat is in proximity to the finger and under the influence of the inherent resiliency of the spring 38, force the check or token, should the latter reach this point in the 10 operation of the machine, through an opening 46 (see also Figure 11) in the plate 16 and thereby eject the token from the check carrier at the proper time in the cycle of operation of the device. The finger 45 will be permitted to move 20 in a direction to enter the check seat and force the check therefrom by reason of the projection 46 on the check carrier member 19 passing out of engagement with the body portion of the part 41 of the spring 38 and moving into proximity to the deflected extremity 43. At the time that the finger 45 enters the check seat 24 the magnet 37 will be moved back to its normal position to stand adjacent the side of the check seat or from the position shown in Figure 4 back to 30 the position shown in Figure 1.

The forward movement of the check carrier member 19 will be limited by means of a pin 47 carried by the check carrier member 19 engaging the end of a slot 48 (see Figure 3) in the plate 16. Likewise the return movement under the stress of the spring 26, may be limited by the engagement of the pin 47 with the other end of the slot 48, instead of the check carrier being limited in its return movement by the engagement of the knob or handle 22 with the end of the slot 21. 40

The member 17 is provided in its lower edge with a series of ratchet teeth 49 (see particularly Figure 3) with which a pawl 50 co-operates, the pawl being controlled by a spring 51. This pawl 50 is so arranged and the number of teeth 49 are such that after the pawl passes over one of the teeth 49 the check carrier 19 cannot be returned until it has reached the limit of its movement in a forward direction and sufficiently far to cause the pawl 50 to pass out of engagement with the teeth 49 to be reversed by the spring 51 so that the check carrier 19 may be returned to normal position. 50

The reciprocatory movement of the check carrier 19 is transmitted to an arm or lever 52 which is pivotally mounted as at 53 to a fixed support and the other end of the lever may be connected to the mechanism which is to be operated. A link 54 is pivotally connected by one end as at 55 with the lever 52, and this link is preferably provided with a slot 56 therein, and into which slot the pin or projection 47 carried by the check carrying member or slide 19 projects. 55

In the event that a washer 57 is inserted in the check seat, the body portion thereof will engage the projection 31 to withdraw the lug or projection 33 carried by the spring 30 from the slot 35 in the check carrying member 19, but as soon 70 as the opening in the washer is in alignment with the lug or projection 31, the spring 32 will cause the lug to enter the opening in the washer (see Figure 10) and thereby lock the washer against further advancement. At the same time the pro- 75

jection 33 on the spring 30 will again enter the slot 35, thereby permitting the lug 31 to assume a locking position with respect to the washer. The lug or projection 31 is of a beveled or tapered construction to permit the check carrier 19 to be retracted so as to move the washer back to a position to be removed from the check seat. When a check is inserted in the openings 23 of the casing 20 and the check carrier 19 advanced, a portion 58 (see particularly Figure 10) forming one of the walls of the check seat will enter the slot in the face plate 15 and thereby prevent the insertion of another check into the casing 20 (see also Figure 3). The upper edge of the portion 15 58 of the check carrier is provided with a notch 59 so located that in the event a check 60 of improper diameter (see Figures 10 and 11) is inserted in the check seat, the end 61 of a locking dog 62 will enter thereinto and lock the check carrier against advancement. This dog 62 is pivotally mounted as at 63 and is provided with a lug or pin 64 (see also Figure 1) which passes through a slot 65 in the member 17 and into a position to be engaged by a spring 66 that is anchored as at 67. The spring tends normally to lower the end of the dog 62 to a position that it will enter the notch 59.

When a proper check or token is inserted in the check seat and the check carrier 19 advanced a portion 68 of the check carrier 19 will engage a cam shaped portion 69 of the dog 62 and raise the latter against the stress of the spring 66, but as the portion 68 passes out of engagement with the cam shaped portion 69 of the dog the end 61 of the dog would have a tendency to be forced downwardly by the spring 66, and the periphery of the coin or check will engage the cam shaped portion 69 and again raise the end 61 so as to hold the dog 62 inoperative and in a position that it will not lock the check carrier 19 against advancement. However, if the diameter of the check or token in the check seat 24 is not a proper one, after the portion 68 of the check carrier passes out of engagement with the cam shaped portion 69 of the dog 62, the spring 66 will move the dog downwardly so that the end 61 thereof will enter the notch 59 and thereby lock the check carrier against advancement.

In the event that a thin check or token is inserted in the check seat, the projection 31 on the spring 30 will be held by the spring within the check seat and the edge of the check seat will abut the projection 31 and also the projection 33 on the spring 30 will be held within the slot 35 of the check carrier 19 and the end of the slot 35 will contact with the projection 33.

It will therefore be manifest that with this improved construction the checks will be detected and all checks or tokens except the ones of proper size and denomination, will be prevented from entering the mechanism.

While the preferred form of the invention has been herein shown and described, it is to be understood that various changes may be made in the details of construction and in the combination and arrangement of the several parts, within the scope of the claims, without departing from the spirit of this invention.

What is claimed as new is:

1. In combination, a check carrier having a check seat, a locking device normally limiting the movement of the check carrier in the absence of a proper check in the seat, means connected with said locking device and adapted to be engaged by a lateral face of the check to render

the locking device inactive, there being a delivery outlet through which the check is adapted to pass when the check seat is in alignment with said outlet, an ejector for displacing the check laterally from its seat and delivering the same through said outlet, and means responsive to the actuation of the check carrier for temporarily rendering said ejector inactive.

2. In combination, a check carrier having a check seat, a locking device normally limiting the movement of the check carrier in the absence of a proper check in the seat, means connected with said locking device and adapted to be engaged by a lateral face of the check to render the locking device inactive, there being a delivery outlet through which the check is adapted to pass when the check seat is in alignment with said outlet, means responsive in its operation to the actuation of the check carrier for displacing the check laterally from its seat and delivering the same through said outlet, the last said means embodying an ejector, means tending normally to move the ejector in a direction transverse to the direction of movement of the check in the check carrier, and means operatively connected with the check carrier and operating to temporarily move said ejector against the stress of the last said means to permit the check to move to a position adjacent said delivery outlet to be ejected there-through by said ejector.

3. In combination, a check carrier having a check seat, a locking device normally limiting the movement of the carrier in the absence of a proper check in the seat, means connected with said locking device and adapted to be engaged by a lateral face of the check in the seat to render the locking device inactive, there being a delivery outlet through which the check is adapted to pass when the check seat is in alignment with said outlet, an ejector for displacing the check laterally from its seat and delivering the same into said outlet, means responsive in its operation to the actuation of the check carrier for temporarily rendering the ejector inactive, and a magnet arranged adjacent the path of movement of the check in the carrier for laterally removing an improper check from the check seat before said seat moves into alignment with said delivery outlet.

4. In combination, a check carrier having a check seat, a locking device normally limiting the movement of the carrier in the absence of a proper check in the seat, means connected with said locking device and adapted to be engaged by a lateral face of the check in the seat to render the locking device inactive, there being a delivery outlet through which the check is adapted to pass when the check seat is in alignment with said outlet, means separate from the said locking device and responsive in its operation to the actuation of the check carrier for displacing the check laterally from its seat and delivering the same into said outlet, a bodily movable magnet arranged adjacent the path of movement of the check in the check seat for laterally removing an improper check from the check seat before said check seat moves into alignment with said delivery outlet, and means for thus bodily moving said magnet.

5. In combination, a check carrier having a check seat, a locking device normally limiting the movement of the carrier in the absence of a proper check in the seat, means connected with said locking device and adapted to be engaged by a lateral face of the check in the seat to render the locking device inactive, there being a delivery outlet through which the check is adapted to pass

- when the check seat is in alinement with said outlet, means separate from the said locking device and responsive in its operation to the actuation of the check carrier for displacing the check laterally from its seat and delivering the same into said outlet, a bodily movable magnet for laterally removing an improper check from the seat before said check seat moves into alinement with said delivery outlet, means tending normally to move said magnet adjacent the path of movement of the check in said check seat, and means for moving the magnet in the opposite direction.
6. In combination, a check carrier having a check seat, a locking device normally limiting the movement of the carrier in the absence of a proper check in the seat, means connected with said locking device and adapted to be engaged by a lateral face of the check in the seat to render the locking device inactive, there being a delivery outlet through which the check is adapted to pass when the check seat is in alinement with said outlet, means separate from the locking device and responsive in its operation to the actuation of the check carrier for displacing the check laterally from the seat and delivering the same into said outlet, a bodily movable magnet for laterally removing an improper check from the seat before said check seat moves into alinement with said delivery outlet, means tending normally to move said magnet adjacent the path of movement of the check in said check seat, and means connected with the check carrier and adapted to engage and move the magnet support for moving the magnet in one direction.
7. In combination, a reciprocable slide having a check seat therein provided with an entrance opening and open sides, a stop for limiting the movement of the slide in the absence of a proper check in said seat, means adapted to be engaged by a lateral face of a check in the seat to render the said locking means inactive, there being a delivery outlet into alinement with which the check seat is movable, a spring actuated ejector adapted to engage a lateral face of the check and eject the same laterally from said seat to said delivery outlet, and means carried with the check carrier slide and adapted to engage a portion of said ejector and move the ejector into an inoperative position against the stress of said spring until the check assumes a position adjacent said delivery outlet.
8. In combination, a reciprocable slide having a check seat therein provided with an entrance opening and open sides, a stop for limiting the movement of the slide in the absence of a proper check in said seat, means adapted to be engaged by a lateral face of a check in the seat to render the said limiting means inactive, there being a delivery outlet into alinement with which the check seat is movable, a spring actuated ejector adapted to engage a lateral face of the check and eject the same laterally from said seat to said delivery outlet, means carried with the check carrier slide and adapted to engage a portion of said ejector and move the ejector into an inoperative position against the stress of said spring until the check assumes a position adjacent said delivery outlet, and a magnet arranged adjacent the path of movement of the check in the check seat and operating to laterally remove an improper check from said seat before the latter reaches said delivery outlet.
9. In combination, a reciprocable slide having a check seat therein provided with an entrance opening and open sides, a stop for limit-
- ing the movement of the slide in the absence of a proper check in said seat, means adapted to be engaged by a lateral face of a check in the seat to render the said limiting means inactive, there being a delivery outlet into alinement with which the check seat is movable, a spring actuated ejector separate from the said limiting means and adapted to engage a lateral face of the check and eject the same laterally from said seat to said delivery outlet, means carried with the check carrier slide and adapted to engage a portion of said ejector and move the ejector into an inoperative position against the stress of said spring until the check assumes a position adjacent said delivery outlet, a bodily movable magnet arranged adjacent the path of movement of the check in the check seat and operating to laterally remove an improper check laterally from said seat before the latter reaches said delivery outlet, and means connected with said check carrier for laterally moving said magnet.
10. In combination, a check carrier having a check seat, a locking device normally limiting the movement of the carrier in the absence of a proper check in the seat, means connected with said locking device and adapted to be engaged by a lateral face of the check in the seat to render the locking device inactive, there being a delivery outlet through which the check is adapted to pass when the check seat is in alinement with said outlet, an ejector separate from said locking device for displacing the check laterally from its seat and delivering the same into said outlet, means connected with the carrier and responsive to the actuation of the check carrier for temporarily rendering the ejector inactive, a magnet arranged adjacent the path of movement of the check in the carrier for laterally removing an improper check from the check seat before said seat moves into alinement with said delivery outlet, and means for stripping the check from said magnet after the check has been removed thereby from the check seat.
11. In combination, a check carrier slide having a reciprocable check seat, a locking device normally limiting the movement of the carrier in the absence of a proper check in the seat, means connected with said locking device and adapted to be engaged by a lateral face of the check in the seat to render the locking device inactive, there being a delivery outlet through which the check is adapted to pass when the check seat is in alinement with said outlet, means separate from said locking device and responsive in its operation to the actuation of the check carrier for displacing the check laterally from its seat and delivering the same into said outlet, a bodily movable magnet for laterally removing an improper check from the seat before said check seat moves into alinement with said delivery outlet, means tending normally to move said magnet adjacent the path of movement of the check in said check seat, means for moving the magnet in the opposite direction, and a stripping device for removing the check from said magnet when the check is removed from the seat by the magnet, said stripping device and said magnet being movable one with relation to the other.
12. In combination, a reciprocable slide having a check seat therein open at the side, means for limiting the movement of the slide in the absence of a proper check in the seat, means separate from said locking means for ejecting a proper check laterally from the seat at a prede-

terminated time in the cycle of operation of the slide, a magnet adjacent the path of movement of an open side of the seat for laterally removing an improper check from said seat, the said magnet being mounted upon said ejecting means and for bodily movement towards and away from the open side of said seat, means for thus moving the ejecting means and with it the magnet, a stationary element arranged in the path of movement of the check by the magnet and adapted to engage a portion of such check to strip or detach the check from the magnet.

13. In combination, a reciprocable slide having a check seat therein open at the side, means for limiting the movement of the slide in the absence of a proper check in the seat, means separate from the said ejecting means for ejecting a proper check laterally from the seat at a predetermined time in the cycle of operation of the slide, a magnet connected to and movable with said ejecting means and disposed adjacent the path of movement of an open side of the seat for laterally removing an improper check from said seat, the said magnet being bodily movable towards and away from the open side of said seat, means for thus moving the ejecting means and with it the magnet, a stationary element arranged in the path of movement of the check by the magnet and adapted to engage a portion of such check to strip or detach the check from the magnet, said magnet being of a substantial U shape and said stripper constituting a finger adapted to pass between the legs of said magnet.

14. In combination a reciprocable slide, a check seat therein having open sides, means for limiting the reciprocation of the slide in the absence of a proper check in said seat, said limiting means being inactive until the slide is moved and embodying a laterally movable stop movable into and out of the path of movement of a shoulder on the slide, a projection carried with said stop and movable into the check seat through one side thereof to be engaged by a lateral face of a proper check and shifted thereby to move the said stop into an inactive position, an ejector for laterally ejecting a proper check from said check seat, and means for temporarily rendering said ejector inactive when the slide is moved.

15. In combination a reciprocable slide, a check seat therein having open sides, means for limiting the reciprocation of the slide in the absence of a proper check in said seat, said limiting means embodying a laterally movable stop movable into and out of the path of movement of a shoulder on the slide, a projection carried with said stop and movable into the check seat through one side thereof to be engaged by a lateral face of a proper check and shifted thereby to move the said stop into an inactive position, means separate from said limiting means for laterally ejecting a proper check from said check seat, and magnetic means for laterally withdrawing from said seat improper checks which are capable of rendering said stop inactive.

MYRON H. RICHARDSON.
ALBERT E. GEBERT.
